UNITED STATES PATENT OFFICE.

DAVID L. OSBORN, OF KANSAS CITY, MISSOURI, ASSIGNOR TO HARRY MESCHLE, OF SAME PLACE.

STOVE-PIPE DAMPER.

SPECIFICATION forming part of Letters Patent No. 428,129, dated May 20, 1890.

Application filed October 25, 1889. Serial No. 328,173. (No model.)

To all whom it may concern:

Be it known that I, DAVID L. OSBORN, of Kansas City, Jackson county, Missouri, have invented certain new and useful Improvements in Stove-Pipe Dampers, of which the following is a full, clear, and exact description, reference being had to the accompanying drawings, forming a part hereof.

My invention consists of a new and improved damper and ventilator to be applied to stoves, furnaces, boilers, and heating apparatuses, whereby the heat, draft, and ventilation may be regulated as desired and by will of operator, of which the following is a full, clear, and exact description.

My invention consists of an improved device and arrangement for regulating the heat, draft, and ventilation by means of two valves—the main and auxiliary valve, the main valve and its relative adjustments so arranged with its relative connection that it operates the auxiliary valve in its movements and adjustments, as hereinafter described.

First. The valves are arranged in their relative position in the smoke pipe or flue so as to admit and allow the valves to oscillate in and out as desired. Second. The valve-seats are created and formed by removing a circular piece, the size being one-half of the dimension of the circumference of pipe. Third. Main valve is formed from a piece of iron one-half inch larger in diameter than the incision in the smoke-pipe, and so arranged in its construction as to allow one half of the valves to be inserted in the opening in smoke-pipe and to rest upon its seat on or within the side of the smoke-pipe, and the other half to rest upon its seat on the outside of smoke-pipe, which device effectually closes the incision in pipe resting upon its seat when closed. Fourth. The main valve is hung or hinged at its diameter upon pivots to the center of opening or valve-seats, and is so secured as to admit the valve to open and close in its oscillating movements. Fifth. The auxiliary valve is arranged, placed, and secured above the main valve in smoke-pipe, and its connections are adjusted to receive the reciprocative movements with the movement of the main valve. Sixth. The auxil-

iary valve is formed from a piece of iron cut to the radius of the pipe it is to perform its work. Seventh. The auxiliary valve is hung and hinged upon a rod passing through the auxiliary valve at the center of smoke-pipe and so arranged as to stand upright or vertical. Eighth. Projecting arm is then secured to the auxiliary valve at its center and projects out one-half of the radius of the smoke-pipe, or equal to three-fourths of diameter of smoke-pipe. Ninth. The projecting arm of auxiliary valve hangs downward and is so adjusted to the main valve that the movement of the main valve is transmitted to the auxiliary valve in its relative position. When the main valve is closed, the auxiliary is open, and, vice versa, main valve open, auxiliary valve closed. Tenth. The device and arrangement of the connecting-rod that joins and unites the two valves—the main and auxiliary valve—is formed by connecting-rod secured or toggled to the projecting arm of auxiliary valve, and then passes downward, the auxiliary remaining upright, or vertically passing through a seat formed by a bracket secured to the main valve to pass upward and downward on the connecting-rod, which transmits its motions to the auxiliary valve.

Referring to the drawings by letter, Figure 1 is a perspective view of my damper located in a short section of pipe. A is the pipe. E is the bearing of the rod that holds the auxiliary valve in position in the pipe. G is the front portion of the damper. a is the handle by which the damper is opened and closed. d is the head of the pivot, to which arm B (seen at Fig. 2) is connected to the damper. F is a seat or hinged joint on which the damper gets its oscillating movement.

Fig. 2 is a sectional view of my invention, showing the interior arrangement of its different parts; D, an oscillating damper; E, a rod passing through the center of the pipe, on which the auxiliary damper operates. C is an extended flap, hinged at b to arm B, connecting the two dampers together.

Fig. 9 is the upper portion of the damper lapping over the cut-away portion of the stove-pipe when in a closed position; Fig. 10, the lower portion of the pipe cut away, the

dotted lines showing the edge of the damper when in a closed position.

Having thus described my invention, that which I claim, and desire protection in by 5 Letters Patent of the United States, is—

In a stove-pipe damper, the combination of a main damper pivoted midway of its length in the pipe, the upper half of the said damper engaging the interior and the lower half the 10 exterior of the pipe, a semicircular auxiliary damper pivoted above the main damper and

having a downwardly-extending flap thereon, and an arm pivoted to the upper portion of the main damper and having a pivotal connection with the flap on the auxiliary damper. 15

In testimony whereof I affix my signature in presence of two witnesses.

DAVID L. OSBORN.
